UNIFORM BOBBIN FEED FOR PICKS
AND PICK LOOMS

Elliot A. Santon, Worcester, Mass., assignor to
Crompton & Knowles Loom Works, Worcester,
Mass., a corporation of Massachusetts

Application April 2, 1947, Serial No. 738,811

14 Claims. (Cl. 139—232)

1

This invention relates to improvements in filling mixing pick and pick weft replenishing looms and it is the general object of the invention to provide such a loom with a multi-stack magazine controlled in such manner that it will deliver bobbins according to a predetermined sequence relatively to the stacks for successive replenishing operations of the loom thereby permitting full use of the bobbin storage capacity of the magazine.

In prior Patent No. 2,380,544 there is set forth a pick and pick filling mixing automatic loom having a multi-stack magazine provided with bobbin releasers and a selector therefor moved by a cam operating independently of transfer. The bobbins are drawn from the stacks with which the selector happens to be in register when the three shuttles of the loom need replenishment. This results in a selection of bobbins which so far as the order of drawing from the stacks is concerned is hit or miss, but satisfactory in many instances. In other instances, however, it is found that all the bobbins will be drawn from one stack while several bobbins still remain in the other stacks. When this happens the loom is stopped by the filling stop motion without being able to use all the bobbins in the magazine.

The actuating mechanism for the selector positioning cam shown in the aforesaid patent is operated by shifting shuttle boxes which give a comparatively slow advantageous feed movement to the pawl which operates the ratchet wheel connected to the cam. It is an important object of the present invention to utilize this slow or low rate feed of the ratchet wheel in connection with control means for the pawl to move the selector in such manner as will draw bobbins uniformly from the several stacks of the magazine, thereby avoiding premature depletion of one stack.

The usual multi-stack stationary reserve bobbin magazine includes in its construction a shaft which is rocked from normal to transfer position when the magazine is set for a replenishing operation. It is another object of the present invention to cause the shuttle boxes to give regularly recurring but normally idle working strokes to the feed pawl for the ratchet wheel, and move the pawl into operative position relatively to the ratchet wheel on transferring beats of the loom by means of a control derived from the aforesaid shaft when it moves to transfer position.

In the preferred form of the invention the feed pawl normally hangs in a low position be-

2

low the ratchet wheel and is lifted to operating position when the aforesaid shaft moves to transfer position. In the modified form of the invention the pawl is held in high position above the ratchet wheel by a connection to the shaft during non-replenishing beats of the loom, but when replenishment occurs the connection descends and permits the pawl to fall into operating position.

The shuttle boxes start their shifting movements when the lay is substantially on bottom center and moving forwardly. The magazine will ordinarily be set for transfer at or prior to this time. As the lay reaches front center the magazine is reset and the aforesaid shaft returns to normal position, thereby losing its control of the pawl. The timing of the parts is such, however, that the boxes when shifting cause the pawl to engage one or another of the teeth of the ratchet wheel before the magazine is reset, and the pawl will remain in driving relation with respect to the ratchet wheel after resetting of the magazine.

In the modified form of the invention the pawl not only moves angularly around the ratchet wheel axis but also rises when having a working stroke. The connector from the shaft to the pawl is lifted when the magazine is reset at front center, but by this time the pawl will have risen to a sufficiently high position to prevent the connector from lifting it out of driving relation with the ratchet wheel, and the latter will continue to be moved by the pawl after completion of transfer and resetting of the magazine at front center.

With these and other objects in view which will appear as the description proceeds, my invention resides in the combination and arrangement of parts hereinafter described and set forth.

In the accompanying drawings, wherein two forms of the invention are set forth,

Fig. 1 is a front elevation of a loom having the preferred form of the invention applied thereto,

Fig. 2 is an enlarged side elevation of part of the magazine looking in the direction of arrow

45 2, Fig. 1,

Fig. 3 is a diagrammatic view showing the pawl, ratchet wheel, and associated parts of the preferred form in two different positions,

Fig. 4 is a view similar to part of Fig. 2 but showing the modified form of the invention,

Fig. 5 is a detailed front elevation of the positioning cam and associated parts looking in the direction of arrow 5, Fig. 4, and

Fig. 6 is a view similar to Fig. 3 but showing the modified form of the invention.

Referring particularly to Fig. 1, a harness and shuttle box control mechanism K is shown at the left end of the loom and a multi-stack stationary magazine M at the right end. The lay L reciprocates in the usual manner and has right and left groups of shifting shuttle boxes RG and LG, respectively. There are two shuttle boxes in each gang and each gang shifts in a four-pick cycle so that it is up for two successive picks and then down for the next two successive picks. The cycles of the two gangs are out of step with each other by one pick, and when one gang shifts the other is at rest with respect to the lay. The loom operates with three shuttles not shown which follow each other in rotation and all carry weft of the same kind.

The pattern mechanism K is built to effect shifting of the shuttle boxes according to the sequence described and includes in its construction a lever 10 which rocks about an axis 11. A box lifter chain 12 leads from lever 10 to gang LG in usual manner to lift the latter during an interval occurring every fourth pick of the loom while the lay moves from bottom to top center. The gang LG has its shifting movements on those beats of the lay when replenishing operations can occur and at a time when the gang RG is necessarily at rest with respect to the lay to permit transfer.

The magazine M is of the stationary type and preferably has provision for holding four stacks of similar reserve bobbins each provided with a releaser 15 and cradle 16. When a releaser is raised it rocks the corresponding cradle in a direction to receive a bobbin from the corresponding stack, after which the releaser is lowered to return the cradle to its normal position for the purpose of discharging the previously received bobbin to permit it to move to transfer position. When a releaser returns to normal down position it effects a clockwise rocking of a top shaft 17, Fig. 1, to transfer position to lift a transfer latch 18 to transfer position for engagement with a bunter 19 on gang RG. At the same time a shuttle feeler 20 moves rearwardly, to the left in Fig. 2, and a rod 21 controlling a bobbin butt giveaway 22 moves down, as set forth in patent to Lauzon No. 1,261,563. At front center on a transfer beat, feeler 20 is pushed forwardly by the lay to return shaft 17 to normal position and raise rod 21. Shaft 17 ordinarily rocks to set the magazine for transfer before the lay reaches bottom center, that is, before gang LG starts to shift up.

The selector mechanism for determining which of the releasers shall be raised and lowered is designated generally at 25 and includes a rod 26 slideable longitudinally on the magazine and provided with a collar 27 grooved to receive the upper end of a positioning lever 28 pivoted on the magazine. A spring 29 tends normally to move the upper end of lever 28 forwardly, or to the right, as viewed in Fig. 2.

The selector has front and back fingers 30 and 31, respectively, which register one at a time with the releasers. When the weft detector D indicates weft exhaustion one or the other of these fingers raises the releaser registered therewith as gang RG rises on one front center and then immediately lowers the raised releaser before the next front center to set the magazine for transfer.

The selector can be moved to four different longitudinal positions by progressive step by step turning of a positioner cam 35. This cam ro-

tates on a fixed stud 36 and has a long high dwell 37, intermediate short dwells 38 and 39, and a long low dwell 40. The cam effects movement of the previously described lever 28 to determine the position of the selector. The cam is fixed to a ratchet wheel having eight teeth described in detail hereinafter. A lock wheel 43 and lock 44 yieldingly hold the cam, ratchet wheel and selector in their several positions.

A lever 45 pivoted at 46 on the loom frame is connected to box chain 12 by a rigid link 47 and is attached to a connection 48 flexible in part and extending to the magazine end of the loom. When chain 12 lifts gang LG it causes lever 45 to pull connection 48 toward mechanism K.

The matter thus far described is of usual construction and may be made according to the aforesaid patent.

In carrying the preferred form of the invention into effect I mount a lever 50 loosely on stud 36 and attach the connection 48 to the lower end of lever arm 51. A spring 52 anchored as at 53 normally tends to turn the lever 50 in a counter-clockwise direction as viewed in Fig. 2 and assists in keeping the connection 48 taut.

The ratchet wheel 54 is secured to the cam 35 and has its teeth pointing in a direction to cooperate with a pawl 55 pivoted at 56 on lever 50 when the latter turns clockwise, Fig. 2. A connector designated generally at 57 includes a lower rod 58 connected to the pawl and a tension spring 59 connected to an arm 60 secured to the shaft 17. When the latter is in its normal position the connector 57 is down and the pawl 55 falls away from the ratchet wheel 54. As the connection 48 is drawn to the left as viewed in Fig. 2 every fourth pick of the loom it rocks lever 50 to move pawl 55 to the left in a clockwise direction, but the pawl normally traverses a path below the ratchet wheel and out of engagement with it.

When the magazine is set for transfer, however, shaft 17 moves to its transfer position preferably prior to the start of shift of gang LG and in doing so lifts the connector 57 to raise the pawl 55 into operative relationship with respect to the ratchet wheel 54. As lever 50 rocks due to shifting of the gang LG the pawl will advance the ratchet wheel one-eighth of a turn. In doing so it moves downwardly and places the spring 59 under some tension, which, however, is not enough to disturb the setting of shaft 17. The latter will return to its normal position with attendant descent of connector 57 when the lay reaches front center and the magazine is reset, but at this time the pawl is still engaged with one or another of the teeth of the ratchet wheel 54 and remains engaged with the ratchet wheel during continued rocking of lever 50 despite the slackness of connector 57.

As soon as gang LG starts to move down spring 52 will return lever 50 to its normal position as shown in Fig. 2, thereby pulling the pawl back on its return stroke, and slackness of connector 57 will permit the pawl to fall to inoperative position. Thereafter it will continue to have normally inoperative working strokes every fourth pick of the loom until the next transfer is called.

Turning of the ratchet wheel causes a corresponding movement of the cam 35 the effect of which is to change the registry of the selector with respect to the releasers. It is in this way that successive replenishing operations produce a progressive step by step movement of the cam 75 to change registry of the selector with the re-

leasers in a given sequence which, because of the contour of the cam, draws bobbin uniformly from the various stacks of the magazine.

In the modified form of the invention the pawl and its ratchet remain more or less as set forth in the previously mentioned patent. A lever 65 similar to lever 50 is mounted on stud 36 and has an upright arm 66 attached to the connector 48. A spring 67 anchored as at 68 normally tends to turn lever 65 in a clockwise direction as viewed in Fig. 6. The arm 70 of lever 65 has a pawl 71 pivoted thereto as at 72 for cooperation with a ratchet wheel 73 similar to ratchet wheel 54 but having its teeth pointing in the opposite direction.

In this modified form of the invention control for the pawl is derived from the previously mentioned rod 21. This control includes a head 75 held in vertically adjusted position on rod 21 by a set screw 76 and provided with a lift finger 77 which extends from the head to a position under pawl 71. When the top shaft 17 which controls rod 21 is in its normal position the latter will be up and the finger 77 will therefore hold the pawl above the ratchet wheel 73 and cause it to traverse normally idle working strokes over the top of the ratchet wheel. When the magazine is set for transfer, however, rod 21 descends, thereby lowering finger 77 and permitting pawl 71 to fall into operative engagement with the ratchet wheel 73. As in the preferred form of the invention this last operation will occur when the loom is approximately at bottom center position, or slightly theretofore, and the next ensuing backward movement of pawl 71 due to shift of gang LG will rock the ratchet wheel 73 for one-eighth of a turn in a counter-clockwise direction as viewed in Fig. 6.

It will be understood that when the lay reaches front center position on a replenishing operation rod 21 will have been lifted to its normal high position due to return of shaft 17 to its normal position. It will be apparent from Fig. 6, however, that when pawl 71 has an operative working stroke it is raised bodily with respect to the finger 77 and will have attained a sufficiently high position at the time of front center to prevent unseating thereof relatively to ratchet wheel 73 by the upwardly moving finger 77. On the return or idle stroke of the pawl it will move downwardly into engagement with finger 77 and the latter will hold up the free end of the pawl and cause it to miss the nearest ratchet tooth on its next working stroke.

From the foregoing it will be seen that I have provided simple means to give the feed pawl slow gradual working strokes by connections actuated by shifting shuttle boxes, together with controls by which the pawl can operate on replenishing beats only of the loom. The positioning cam, the ratchet wheel, and the pawl may be considered as an actuating or positioning unit for the selector which makes regularly recurring attempts to change the position of the selector, these attempts normally being nullified due to the fact that the pawl is kept in a non-operative position by the magazine but becoming operative on replenishing beats of the loom. In the preferred form of the invention the pawl is below the ratchet wheel and has its idle strokes along the under side of the wheel. When the shaft 17 rocks to transfer position, however, the pawl is lifted into engagement with the ratchet wheel at a time which occurs sufficiently early to permit correct placement of the pawl with respect

to the tooth which it is intended to engage. In the modified form of the invention the pawl is normally held in high position and moves along a path having an upward as well as rearward component as viewed in Fig. 2, and when shaft 17 rocks at transfer position the controller allows the pawl to fall into driving position with respect to the ratchet wheel. Thereafter as the pawl has its working stroke it also rises and when shaft 17 returns to normal the pawl will have been risen sufficiently high so that it is not unseated by the controller.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom having a reserve bobbin magazine provided with a plurality of bobbin releasers and a releaser selector movable to register with the releasers one at a time, the magazine having a part movable from normal to transfer position preparatory to a weft replenishing operation of the loom, a positioner for the selector movable from one position to another position thereof to cause the selector to change its registry with the releasers, shuttle boxes which shift in a given direction when said part is in transfer position, actuator mechanism for the positioner operatively connected to the shuttle boxes and given a normally inoperative movement relatively to the positioner when said boxes shift in said given direction, and connections between said part and said actuator mechanism causing the latter when moving with said shuttle boxes to move the positioner from said one position to another position thereof.

2. In a weft replenishing loom having a reserve bobbin magazine provided with a plurality of bobbin releasers and a releaser selector movable to register with the releasers one at a time, the magazine having a part moving from normal to transfer position whenever the magazine is set for a replenishing operation, shifting shuttle boxes which have a shifting movement during the time the magazine is set for transfer, a positioner for the selector movable to change registry of the selector relatively to the releasers, actuator mechanism for the positioner operatively connected to said shuttle boxes and having regularly recurring movements simultaneous with shifting of the boxes but normally ineffective to move the positioner, and connections between said part and the actuator mechanism effective when said part is in transfer position to cause said actuator mechanism to move the positioner.

3. In a pick and pick filling mixing weft replenishing loom having a reserve bobbin magazine at one end thereof provided with a plurality of bobbin releasers and a selector movable into registry with the releasers one at a time, shuttle boxes at the opposite end of the loom normally shifting when a weft replenishing operation can occur, a positioner for the selector movable progressively to different positions to effect registry of the selector with the releasers in a given sequence, actuator mechanism for the positioner operatively connected to and moving in time with said shuttle boxes and having movements which are normally idle with respect to the positioner when the shuttle boxes shift, and means effective on successive replenishing operations of the loom to cause said actuator mechanism to move said positioner progressively to said different positions,

4. In a pick and pick filling mixing weft replenishing loom having a lay and a reserve bobbin magazine provided with a plurality of releasers and a selector registerable with the releasers one at a time, shifting shuttle boxes on the lay having regularly recurring shifting movements which occur when the lay is in the forward part of the motion thereof, a positioner for the selector movable progressively to effect registry of the selector with the releasers in a given sequence, a part on said magazine movable from normal to transfer position as the lay advances on weft replenishing beats of the loom, actuator mechanism for the positioner operatively connected to said shuttle boxes and deriving movements therefrom which are normally ineffective relatively to the positioner when said shuttle boxes shift, and connections between said part and the actuator mechanism causing the latter when moving with said shifting shuttle boxes on successive replenishing beats of the loom to move said positioner progressively to effect registry of the selector with said releasers in said sequence.

5. In a pick and pick filling mixing weft replenishing loom having a reserve bobbin magazine provided with a plurality of bobbin releasers and a selector registerable with the releasers one at a time, a positioning cam movable progressively to effect registry of the selector with the releasers in a given sequence, a ratchet wheel secured to and moving with said cam, shifting shuttle boxes having regularly recurring shifting movements certain of which occur during replenishing operations of the loom, a pawl for the ratchet operatively connected to the boxes and having recurring working strokes when the shuttle boxes have said certain shifting movements, said working strokes being normally inoperative with respect to said ratchet wheel, and means operative incident to weft replenishing operations to move said pawl into operative relation with respect to the ratchet wheel prior to said certain shifts of said shuttle boxes occurring during replenishing operations to cause working strokes of the pawl to move said ratchet wheel and cam progressively to change registry of the selector relatively to said releasers in said sequence.

6. In a pick and pick filling mixing weft replenishing loom having a reserve bobbin magazine provided with a shaft movable from normal to transfer position incident to a weft replenishing operation of the loom, the magazine having a plurality of bobbin releasers and a selector registerable with the releasers one at a time, a positioning cam movable progressively to different positions to effect registry of the selector with the releasers in a given sequence, a ratchet wheel moving with the cam, a pawl for the ratchet wheel, shifting shuttle boxes having shifting movements during weft replenishing operations of the loom and operatively connected to the pawl and giving the latter movements normally idle with respect to the ratchet wheel when the shuttle boxes have said shifting movements, and connections between said shaft and pawl effective when said shaft moves to transfer position incident to replenishing operations to move said pawl into working relationship with respect to the ratchet wheel and cause movement of the latter and the cam progressively to said different positions to effect registry of the selector with the releasers in said sequence.

7. In a weft replenishing loom having actuator mechanism to shift shuttle boxes at one end thereof and having a magazine provided with a

plurality of stacks of reserve bobbins at the opposite end of the loom, a bobbin releaser for each stack, a selector for the releasers capable of registering with all of said releasers one at a time, positioning mechanism interposed between said selector and said actuator mechanism, said positioning mechanism including an element movable progressively and operatively connected to said selector to effect movement of the latter into registry with the releasers one at a time according to a given sequence, an operator for the positioning mechanism caused by the shuttle box actuator mechanism to have normally idle strokes relatively to the positioning mechanism, and means effective on replenishing beats only of the loom causing strokes of the operator to be operative relatively to the positioning mechanism to give said element progressive movements.

8. In a weft replenishing loom having shifting shuttle boxes at one end thereof operated by actuator mechanism which periodically shifts the shuttle boxes, a magazine at the other end of the loom having a plurality of stacks of reserve bobbins, a bobbin releaser for each stack, a selector movable progressively to different positions to register with said releasers in a given sequence, a positioning unit for the selector rotatably mounted on the magazine and including a ratchet wheel and a cam rigid therewith operatively connected to the selector and having steps corresponding to said different positions of said selector, an operating pawl for said ratchet wheel, connections between the shuttle box actuator mechanism and pawl giving the latter periodic working strokes normally inoperative relatively to the ratchet wheel incident to periodic shifts of the shuttle boxes, and means effective on weft replenishing beats only of the loom causing the pawl to have operative working strokes relatively to the ratchet wheel to effect movement of the cam to said different positions thereof.

9. In a weft replenishing loom having shuttle boxes at one end thereof which are shifted periodically with respect to the lay by an actuator mechanism, the loom having a magazine at the other end thereof provided with a plurality of stacks of reserve bobbins each having a bobbin releaser and a releaser selector capable of registering with the releasers one at a time in a given sequence, a positioner for the selector having a step by step movement and operative due to the successive movements thereof to register said selector with the releasers in said sequence, an operator for the positioner deriving periodic movements from the shuttle box actuator mechanism normally inoperative relatively to the positioner, and means effective on replenishing beats only of the loom to cause movements of the operator to give the positioner step by step movements to register the selector with the releasers in said sequence.

10. In a weft replenishing pick and pick filling mixing loom having a magazine provided with a plurality of bobbin releasers and a selector registerable with the releasers one at a time, shuttle boxes at the end of the loom opposite the magazine having shifting movements which occur when replenishing operations of the loom can occur, a shaft on the magazine movable from normal to transfer position preparatory to replenishing operations of the loom, a positioning cam for the selector below the shaft and movable progressively to a plurality of positions to effect registry of the selector with the releasers one at a time in a given sequence, a ratchet wheel mov-

ing with the cam, a pawl operatively connected to and having working strokes below and inoperative relatively to the ratchet wheel when the shuttle boxes have said shifting movements, and connections between said shaft and pawl effective when said shaft moves to transfer position on successive replenishing beats of the loom to lift the pawl into operative relationship with respect to the ratchet wheel and cause the pawl to move the ratchet wheel and positioning cam progressively to cause the selector to register with said releasers in said sequence.

11. In a pick and pick filling mixing weft replenishing loom having a reserve bobbin magazine provided with a plurality of bobbin releasers and a selector registerable with said releasers one at a time, shuttle boxes having shifting movements which occur when replenishing operations of the loom can occur, a positioning cam for the selector below the shaft and movable progressively to different positions to cause the selector to register with said releasers one at a time in a given sequence, a ratchet wheel secured to and moving with said positioning cam, a pawl operatively connected to and having working strokes when the shuttle boxes have said shifting movements, and connections between the shaft and pawl normally causing said working strokes to be above and inoperative relatively to the ratchet wheel when the shaft is in normal position, said pawl tending to fall into operative position relatively to the ratchet wheel, and said connections effective when the shaft moves to transfer position on successive replenishing beats of the loom to allow the pawl to fall into operative position relatively to the ratchet wheel and enable the pawl to cause progressive movements of the ratchet wheel and positioning cam to effect registry of the selector with said releasers in said sequence.

12. In a pick and pick filling mixing weft replenishing loom operating with shuttles which arrive at transfer position every fourth pick only of the loom and having also a multi-stack weft replenishing mechanism provided with bobbin releasers and a selector registerable with the releasers one at a time, a positioner for the selector movable to change registry of the selector relatively to the releasers, an actuator for the positioner having working strokes every fourth pick of the loom which are normally inoperative with respect to the positioner, and means operative on a weft replenishing operation of the loom to re-

late the actuator operatively with respect to the positioner to cause movement thereof to effect said change of registry of the selector relatively to the releasers.

- 5 13. In a pick and pick filling mixing weft replenishing loom operating with shuttles which arrive at transfer position every fourth pick only of the loom and having also multi-stack weft replenishing mechanism provided with bobbin releasers and a selector registerable with the releasers one at a time, a positioner for the selector movable to change registry of the selector relatively to the releasers, an actuator for the positioner having at least one working stroke every 10 four picks of the loom occurring on those picks on which replenishing operations can occur, said working strokes being normally inoperative with respect to the positioner, and means operative on a weft replenishing operation of the loom to cause the working stroke of the actuator then occurring to move the positioner to cause a change in registry of the selector relatively to the releasers.
- 15 14. In a pick and pick filling mixing weft replenishing loom operating with shuttles which arrive one at a time in a replenishing position every fourth pick only of the loom and having also a multi-stack weft replenishing mechanism provided with bobbin releasers and a selector registerable with the releasers one at a time, a positioner for the selector movable to change registry of the selector relatively to the releasers, an actuator having a working stroke normally inoperative relatively to the positioner each time a shuttle 20 is in replenishing position, and means operative on a replenishing operation of the loom occurring when a shuttle is in replenishing position to cause the stroke of the actuator then occurring to move the positioner and thereby effect a change 25 in registry of the selector relatively to the releasers.
- 25 15. In a pick and pick filling mixing weft replenishing loom operating with shuttles which arrive one at a time in a replenishing position every fourth pick only of the loom and having also a multi-stack weft replenishing mechanism provided with bobbin releasers and a selector registerable with the releasers one at a time, a positioner for the selector movable to change registry of the selector relatively to the releasers, an actuator having a working stroke normally inoperative 30 relatively to the positioner each time a shuttle is in replenishing position, and means operative on a replenishing operation of the loom occurring when a shuttle is in replenishing position to cause the stroke of the actuator then occurring to move the positioner and thereby effect a change 35 in registry of the selector relatively to the releasers.
- 30 16. In a pick and pick filling mixing weft replenishing loom operating with shuttles which arrive one at a time in a replenishing position every fourth pick only of the loom and having also a multi-stack weft replenishing mechanism provided with bobbin releasers and a selector registerable with the releasers one at a time, a positioner for the selector movable to change registry of the selector relatively to the releasers, an actuator having a working stroke normally inoperative 35 relatively to the positioner each time a shuttle is in replenishing position, and means operative on a replenishing operation of the loom occurring when a shuttle is in replenishing position to cause the stroke of the actuator then occurring to move the positioner and thereby effect a change 40 in registry of the selector relatively to the releasers.
